METHOD FOR APPLYING A FORM MEMBER
TO A BEAM OR THE LIKE

Fredwill Bittner, Los Angeles, Calif.

Application October 18, 1948, Serial No. 55,126

4 Claims. (Cl. 153—2)

1

This invention has to do with a method for applying a form member to a beam, or the like, and it is a general object of the invention to provide a simple, practical method for applying a board or member such as the base or bottom of a form to a part such as a beam or element of a building.

The present invention is related, generally, to a method for effectively applying parts of a form construction, such as are set forth in my copending application entitled "Form Construction," Serial No. 29,073, filed May 28, 1948, to a beam or structural member such as an I-beam, or the like, so that the form member is accurately and dependably supported beneath the beam.

A further object of the invention is to provide methods for effectively handling hangers included in a form or forming a part of a form, so that they are accurately and securely attached to a beam such as an I-beam, or the like without the use of spacers such as are commonly used to locate form parts relative to a beam. By the present invention benders are provided for applying hangers to a beam so that the hangers are snugly and accurately applied or crimped onto the beam, so that they are effectively secured thereto.

The various objects and features of my invention will be fully understood from the following detailed description of a typical preferred form and application of the invention, throughout which description reference is made to the accompanying drawings, in which:

Fig. 1 is a perspective view of the bottom or base element of a form showing hangers projecting therefrom ready for application to a beam. Fig. 2 is a side elevation of a bottom form member such as is shown in Fig. 1, showing it applied or related to an I-beam with some of the hangers connected with the bottom and in position at the beam some ready for engagement with the beam and one in the course of being made ready to engage the beam. Fig. 3 is a plan view of a portion of a structure such as is shown in Fig. 2, showing the upper end portion of one hanger arranged to extend across the beam and the other in the process of being swung across the beam. Fig. 4 is a view taken transversely of the beam showing a hanger in

the course of being clamped to the beam and bent into position in engagement with the beam. Fig. 5 is an enlarged detailed sectional view of the structure shown in Fig. 4. Fig. 6 is a view of a portion of the structure shown in Fig. 5 showing the parts in the more fully operated position. Fig. 7 is a view taken as indicated by line 7—7 on Fig. 5. Fig. 8 is an enlarged detailed transverse sectional view taken as indicated by line 8—8 on Fig. 5. Fig. 9 is a plan view taken as indicated by line 9—9 on Fig. 5. Fig. 10 is an enlarged view of apparatus shown in Fig. 2, showing it in a more fully operated position, and Fig. 11 is a detailed sectional view taken as indicated by the line 11—11 on Fig. 10.

The present invention can be used to advantage in applying part of the form construction, such as I have hereinabove referred to, to an I-beam, or the like, and for purpose of example 10 the invention will be described in connection with or as being used to apply the bottom or base of a form to an I-beam by means of hangers which project upwardly from the bottom and are engaged with or applied to the upper flange 15 of the beam. In the drawings the form member or bottom is indicated at A and several like hangers B are shown in connection with the bottom. The beam C to which the elements A 20 and B are secured is shown as an ordinary I-beam having a vertically disposed central web 25 and like horizontally disposed upper and lower flanges 11 and 12.

The methods of the present invention are applied successively to the hangers B and it is preferred that the several hangers be alike and therefore I will describe but one hanger and the operations that are performed thereon, it being understood that such description is applicable 30 to each and every one of the hangers.

40 The hanger B shown in the drawings is formed of a length of rod or bar such for example as iron or mild steel, and it has a deformable straight, elongate central or body portion 15, a lower end portion 16 and an upper end or head portion 17. The lower end portion 16 of the hanger may be secured to the bottom A of the form in any suitable manner. In the case illustrated the bottom A is shown as involving an elongate flat board 20 with a flat top 21 and a flat bottom 22. The lower end portion 16 of the

hanger passes through an opening in the board and is hooked around a cross arm 24 engaged under the board in the manner clearly shown throughout the drawings. With the hanger thus initially prepared or applied to the bottom A the body portion 15 of the hanger projects upwardly from the board 20 and in its original form the upper end portion 17 of the hanger is straight and is an integral continuation of the body portion 15 of the hanger.

In accordance with the present invention the first operation performed upon the hanger is bending the hanger to establish a right angle corner 25 between the body portion 15 and the upper end portion 17, and ordinarily it is most convenient to make this bend so that the upper end portion 17 of the hanger extends parallel with the beam and the bend is so located that the lower or bottom edge portion 23 of the portion 17 is in the plane of or is flush with the top 27 of the upper flange 11 of the beam. In practice the hangers are applied to the bottom A so that when the parts are initially positioned at the beam the hangers extend upwardly at opposite sides of the beam at or close to the edges 28 and 29 of the flange 11.

The bender provided by the present invention for making the right angle bend at 25 between the body and upper end portion of the hanger preferably includes an elongate frame 30 with a side channel 31 for reception of the body portion 15 of the hanger and a lever 32 operating relative to the frame. The lever is preferably joined to the upper end of the frame by pivot pin 33 and has a head portion 34 adjacent the point that is pivotally connected to the frame, which head portion is adapted to engage the end portion 17 of the hanger immediately above the upper end of the frame 30 in such manner as to bend the end portion of the hanger over the upper end of the frame, as indicated in Fig. 2 of the drawings. A handle 35 projects from the head 34 of the lever and is of such form and length as to be readily engaged by the operator so that the head can be easily swung in such manner as to effect the desired bend in the hanger.

The bender provided for establishing the bend between the body 15 and end or head portion 17 preferably includes an adjustable stop or leg 36 that depends from the frame 30 to engage or stop against the top or upper side 21 of the bottom A. In the construction illustrated the stop 36 is slidably carried in a guide opening 37 in the frame 30 and a set screw 38 is provided for making the stop secure in the desired position. As the bender is used the body 15 may be temporarily deflected slightly away from the beam.

It will be immediately apparent from Figs. 2 and 10 of the drawings how the bender provided for making the initial bend in the hanger may be easily and quickly applied to the hanger so that the body portion thereof enters the channel 31 while the stop 36 rests on the top of the bottom member A. With the bender thus positioned relative to the hanger simple swinging or turning of the handle 35 in the direction indicated by the arrow in Fig. 2 makes the desired right angle bend or corner 25. The hanger is shown initially bent in the desired manner in Fig. 10 of the drawings where the lower or bottom edge portion 23 of the end portion 17 of the hanger is shown flush with the top 27 of the beam flange 11 while the end portion 17

extends parallel with the beam adjacent the edge 28 thereof. The stop makes it unnecessary to use spacers between the bottom A and the beam.

5 The next operation performed upon the hanger is twisting of the body 15 of the hanger so that the end portion 17 horizontally disposed, as shown in Figs. 2 and 10, is swung from a position parallel with the beam to a position transverse of the beam in engagement therewith and extending across the beam as shown at X in Fig. 3. At Y in Fig. 3 the end portion 17 of a hanger is shown in the course of being swung to a position transverse of the beam. To thus 10 position the upper end portion 17 of the hanger transversely of the beam no tools or equipment are required, since the end portion 17 of the hanger in and of itself forms a convenient lever by which the desired torque can be applied to the 15 body 15 in order to cause permanent distortion thereof. When the upper end portion 17 of the hanger has been moved or swung to the transverse position its end or tip portion 40 projects from the edge of the beam opposite to the edge 28 engaged by the body of the hanger. For instance, as shown in Fig. 4, when the body of the 20 hanger engages or abuts the edge 28 of the beam flange 11 the tip 40 of the hanger portion 17 projects outward from or beyond the edge 29 of flange 11.

The next operation, in accordance with the present invention, is crimping of the tip portion 40 of the hanger so that it is engaged around the edge of the beam at the edge 29 of the beam. 35 In accordance with the preferred form of the invention the tip portion 40 is so crimped or bent as to first extend down past the edge 29 and thereafter extend back or inward under the edge portion of the beam to a position such as is illustrated in Fig. 6 of the drawings. The crimping or bending of the tip 40 of the hanger is performed while the body portion 15 of the hanger is held tight against the opposite edge of the beam.

45 The bender provided by the present invention to clamp the body 15 to the beam and bend the tip 40 of the hanger is shown in Figs. 4, 5, 6, 7, 8 and 9 of the drawings and in the form illustrated it involves, generally, an elongate shank 50 carrying opposed clamp jaws 51 and 52, operating means 53 for operating the clamp jaws relative to each other, and a lever 54 carried by and operable relative to the shank 50 to effect the desired bending of the tip 40 of the hanger.

55 The shank 50 is shown as an elongate bar and one of the jaws is shown fixed on the bar while the other is shiftable along the bar. The jaw 51 which engages the edge of the beam around which the tip of the hanger is to be bent is preferably fixed on one end of the shank 50 while the jaw 52, which engages the opposite edge of the beam is shiftable on the beam. The jaw 52 is shown provided with a guide portion 55 slidably engaged with the shank 50.

60 In accordance with the present invention the shiftable or shiftable jaw 52 is characterized by a base portion 56 projecting from the guide 55 and spaced fingers 57 projecting from the base portion. The fingers 57 are spaced apart so that the body portion 15 of the hanger may be arranged between them and the base portion 56 of the jaw is such as to abut or engage against the hanger portion 15 in order to press or crimp it toward the beam, as shown throughout the drawings. The jaw 51 has one or more fingers 58

opposing the fingers 57 of jaw 52 so that the upper flange 11 of the beam is effectively gripped or embraced when the structure is applied thereto, as shown in the drawings.

The operating means 53 provided for moving the jaws relative to each other is preferably such as to operate the jaws so that they crimp or grip the upper flange of the beam in the desired manner.

In the case illustrated the operating means 53 is a toggle mechanism involving pivotally connected links 60 and 61, a handle 62 projecting from one link, and an adjustable carrier 63 supported by the shank 50 and supporting one of the links. In the case illustrated link 60 is pivotally connected to the carrier 63 while the link 61, which is pivoted to link 60 is pivotally connected to the jaw 52. The carrier 53 is adjustable along the shank 50 and a set screw 65 is provided for setting the carrier in any desired position on the shank. Through this construction the operating means can be adjusted to accommodate beam flanges of various widths and the mechanism is such that it can be set to apply great force to the jaws by suitable operation of the handle 62.

The lever 54 is carried by or on a pivot pin 70 at the end of the shank 50 which carries the jaw 51. The lever is shown as involving a handle 71, a lug 72 projecting laterally from the handle and pivotally connected to the shank 50, and a head 73 projecting from the handle at the point where the lug is located and engageable with the tip 40 of the hanger. The head 73 of the lever 54 is so proportioned and related to the other elements just described that it engages the upper side or upper edge portion of the tip 40 as the tip initially projects from the beam. When the lever or handle 70 is swung in the direction indicated by the arrow in Fig. 5 the head 73 moves down depressing the tip 40 as shown in Fig. 5, and it finally moves to a position where it bends the tip 40 under the flange of the beam, as shown in Fig. 6.

In the preferred form of the invention the head 73 is adjustable or shiftable relative to the lug 72 and handle 71 so that it can be arranged to engage the tip 40 at various points or in various manners, as shown in Figs. 5 and 6 of the drawings. In the particular case illustrated the head 73 has an extension 80 slidably carried on the handle 73 adjacent the lug 72 and through this construction the head can be positioned to project a substantial distance from the lug as shown in Fig. 6, where the mechanism has considerable leverage over the tip 40 and seats it tight against the flange of the beam or it can be arranged in a position such as is shown in Fig. 5 where it projects but a limited distance, in which case it may engage the tip 40 at or close to the point where the tip is bent around the edge of the beam, in order to initially bend the tip over the edge of the beam and effect a snug engagement of the tip with the beam.

From the foregoing description it will be apparent that the method provided by the present invention involves but few simple operations which, when successively performed upon the hanger, establish the hanger on a beam with the upper end of the body of the hanger tight against one edge of the beam while the tip of the hanger is crimped or bent tightly around the other edge of the beam. It will be understood from the drawings how the invention has provided simple apparatus by which the operations or bends re-

quired are easily and accurately formed, to the end that by few simple operations a form member such as the bottom A of a form may be applied to a beam to be accurately located relative to the beam, while at the same time it is effectively secured to the beam in a most secure and dependable manner.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. The method of applying a form member including an upstanding hanger to an elongate beam so said member is spaced beneath the beam including, arranging the hanger at one side of the beam with aligned body and head portions extending vertically and then bending it where the body and head adjoin so the head portion is moved to a horizontal position parallel with the beam, then twisting the body of the hanger to position the head transversely of the beam, and then bending the end of the head portion around the beam at the other side thereof.

2. The method of applying a form member including a deformable hanger with a vertical body and an aligned head portion projecting up from the body to an elongate beam having a top flange including, arranging the body adjacent one edge of the flange to project upwardly at the side of the beam with the head portion above the beam, bending the hanger where the head portion of the hanger joins the body until the head portion extends parallel with the beam, twisting the body of the hanger to position said head portion transversely of the beam, and then crimping the tip of the head portion around the other edge of the flange.

3. The method of applying a form member including a hanger with a vertical elongate deformable body and a head portion projecting up from the body in line therewith to a beam having a top flange including, arranging the body adjacent one edge of the flange with the head projecting above the beam, bending the hanger where the head portion of the hanger joins the body until the head portion extends parallel with the beam, twisting the body of the hanger to position said head portion transversely of the beam, and then crimping the tip of the head portion around the other edge of the flange while the body is held tight against the first mentioned edge of the flange.

4. The method of applying a form member including a deformable hanger with a vertical body and a head portion projecting up from the body in line therewith to a beam having a top flange including, arranging the body adjacent one edge of the flange with the head projecting above the beam, bending the hanger where the head joins the body so the head remains straight and extends parallel with the beam, then twisting the body to position the straight head across the top of the flange in engagement therewith, then bending the tip of the head down at the other edge of the flange while the body is held tight against the first mentioned flange, and then bending the tip under the flange.

FREDWILL BITTNER.
